ATOMIZING NOZZLE

Fred Kurata, Lawrence, Kans., assignor to Kask Technical Corporation, Jackson Heights, N. Y., a corporation of New York

Application August 12, 1948, Serial No. 43,829

9 Claims. (Cl. 299—121)

1

The present invention relates to nozzles for atomizing liquids. Particularly in one aspect this invention relates to such a nozzle in which a vibrating member is employed to bring about the desired degree of atomization. This application is a continuation-in-part of my prior and co-pending application Serial No. 533,720, filed May 2, 1944, now abandoned.

In the commercial atomizing nozzles on the market today in which pressure alone is employed as the atomizing force as contrasted with those in which a gas under pressure is used as the propelling and disruptive agency, the atomization of the liquid is produced by subjecting it to a whirling action before ejecting it from an orifice of the desired shape and size. The whirling motion is imparted to the liquid by passing it under pressure through a chamber of special construction. All of the nozzles of this type are inherently inefficient because of the pressure drop caused by the absorption of energy as fluid friction when the liquid traverses the nozzle chamber.

It is an object of the present invention to produce an atomizing nozzle of a design radically different from that discussed above in which energy losses due to fluid friction are in a large part eliminated.

It is a further object of this invention to produce an atomizing nozzle in which a much lower fluid pressure is required to obtain a certain degree of atomization than is the case with the presently-known types of atomizing nozzles.

It is still another object of the invention to provide an atomizing nozzle of relatively simple and compact construction which brings about a more efficient atomization of liquids than those presently in use.

It is a still further object of the present invention to provide an atomizing nozzle in which the degree of atomization of the liquid can be readily varied.

Another and further object of the invention is to provide an atomizing nozzle which will operate efficiently and bring about a fine degree of atomization of a liquid by using only the force supplied by the liquid under pressure.

Still another object is to provide a nozzle which is applicable to the atomization of a large variety of liquids.

Other and further objects of the invention will be apparent from the detailed description thereof, taken in conjunction with the following drawings, in which:

2

Figure 1 of the drawings is a front elevational view, partly in cross-section, of the invention in which automatic vibration of a valve member is produced by means of a bow spring.

Figure 2 is a plan view of the device illustrated in Figure 1.

Figure 3 is a front elevational view, partly in cross-section, of the invention in which automatic vibration is produced by means of a helical spring.

Figure 4 is a graph of comparative tests between the vibrating type nozzle of the present invention and the most efficient commercial nozzle tested. The abscissa of the graph of Figure 4 is the settling time of the spray produced by the nozzles tested. The ordinate of the graph of Figure 4 is the per cent of the liquid spray which remained in suspension after the designated settling time. Curves A and B are for the vibrating type nozzle and curve C is for the commercial nozzle.

Referring with greater particularity to the embodiment of the invention illustrated in Figure 1, numeral 1 designates a substantially U-shaped or bow spring member having a terminal portion 2 bent inwardly at substantially right angles to the lower leg of the bow spring and another terminal portion 3 extending in a lateral direction.

Terminal portion 2 of spring 1 is rigidly fastened by threaded bolts 4 to a body portion 5 of the atomizing nozzle. Other methods, such as welding, known to those skilled in the art may be used to fasten spring 1 to body portion 5 without departing from the scope of this invention. Body portion 5 is preferably cylindrical in shape but may be polygonal or other shapes, if desired. Body portion 5 contains a chamber 6 which for the most efficient operation of the nozzle is cylindrical and of circular cross-section, although other shapes may be employed. Chamber 6 narrows at one end by means of a conical section to an open cylindrical orifice or aperture 7 of substantially smaller cross-sectional dimension than chamber 6. Chamber 6 and orifice 7 are preferably axially aligned.

Liquid, such as water, under pressure from any suitable source is supplied to chamber 6 by means of a conduit 8, connected thereto by suitable means, such as by threading, as shown in Figure 1. Other means, such as welding, bolting, etc., may be used to connect conduit 8 to chamber 6 without departing from the scope of this invention.

Laterally extending terminal portion 3 of spring member 1 contains an aperture 9 in direct alignment with the axis of orifice 7 and chamber 6 of the nozzle. A valve member 10, preferably having a conically-shaped terminal or end portion 11 and an elongated stem portion 12, extends through aperture 9 and fits tightly therein. Terminal portion 11 of valve member 10 may be of spherical shape without departing from the scope of this invention.

A bracket 13 is rigidly fastened to the spring member 1 adjacent terminal portion 3 by bolts 14 or any other suitable means and a portion 15 thereof extends laterally over the valve stem 12. The laterally extending portion 15 of the bracket 13 contains an aperture 16 in direct axial alignment with aperture 9 and discharge orifice 7. The aperture 16 receives an adjusting screw 17 which may be maintained in any desired position by a lock nut 18. The adjusting screw 17 contacts the end of the valve stem 12 and seats the conically-shaped end portion 11 upon the discharge orifice 7 with any desired degree of force.

When in position, the conical terminal portion 11 of valve member 10 is seated in cylindrical orifice 7 to form a continuous line or knife edge contact between the surface of terminal portion 11 and the outer edge of the mouth of orifice 7. When seated and when in vibration, valve member 10 is axially aligned with, and perpendicular to the plane formed by the mouth of, orifice 16.

In order to secure a rapid vibration of valve member 10 upon its seat in the outlet orifice 7, a resonant system is set up in which the mass of the spring member 1 and elements attached therewith are balanced against the resiliency of the spring so that the system will vibrate freely in a longitudinal direction when as may be demonstrated, for example, by striking it a sharp blow. In actual operation the size of orifice 7, the strength of spring 1, and the mass of spring 1 and valve member 10 are so co-related to one another that the passage of liquid under pressure through the nozzle orifice 7 supplies a force in correct phase relationship to the resonant system so that the same is maintained in forced vibration. The rapid vibration of the valve member 10 upon the discharge orifice 7 breaks up the liquid into a spray-like form.

In general the greater the mass of the vibratory part, the lower will be the frequency of vibration, and the greater the spring force, the higher will be the frequency of vibration. The frequency of vibration will also tend to increase with an increase of liquid pressure at the source, but this factor is usually not as important as the mass of the spring and the parts associated therewith and the spring tension.

Thus it is seen that by varying and balancing the co-acting forces, the operable limits of the device may be widely changed and any desired degree of atomization of the liquid can be procured. For most practical purposes, the frequency of vibration will be maintained within the audio range, and, for example, frequencies of 60 to several thousand cycles per second may be cited.

Figure 3 of the drawings illustrates a modification in which the rapid vibration of the valve member is produced by a helical spring. According to Figure 3, numeral 20 designates a body portion of any desired shape, preferably cylindrical, having a chamber 21 therein and a threaded end section 24. A discharge orifice or

aperture 23 passes through end section 24 in open communication with internal chamber 21. Chamber 21 and aperture 23 are preferably cylinders of circular cross-section and are axially aligned. In the preferred embodiment of the device shown in Figure 3, chamber 21 narrows by the means of a conical or beveled section 22 to aperture 23 in order to minimize frictional losses and turbulence in the flow of liquid 10 through the nozzle.

A perforated housing or cap 26 internally threaded is screwed on to threaded end section 24 of body portion 20. A valve member 27 having a valve head 28 is located centrally within chamber 21 with the valve head 28 seated on the outer edge of discharge orifice 23. That portion of valve head 28 which seats in orifice 23 is preferably conical as indicated by numeral 29. Valve head 28 may be spherically shaped 20 without departing from the scope of this invention.

An important feature of the nozzle is the seating of the conically-shaped valve head 28 on the outer edge of the mouth of orifice 23 to make a line contact or a knife edge contact. Such contact is in contrast to surface contact which would result if the outer edge of orifice 23 had conically-shaped sides parallel to sides 29 of valve head 28. Other important features of orifice 23 and valve head 28 will be discussed hereinafter.

Valve member 27 contains an end section 31 which extends from valve head 28 as shown. A cylindrical-helical spring 32 surrounds end section 31 and seats on a flanged washer 30 on the shoulder of valve head 28. The other end of spring 32 fits in recess 33 and presses against housing or cap 26. In this manner, valve member 27 is urged towards orifice 23 and valve head 28 is seated therein. The housing or cap 26 contains a plurality of openings 34 for the emission of the spray or fog from the cap.

Chamber 21 is recessed at 36 to receive a perforated disk 37. Member 37 has an opening 38 centrally located therein through which valve stem 27 is inserted. The clearance between the walls of opening 38 and valve stem 27 is sufficient to allow free movement of the valve member 27 in a longitudinal direction while restricting its transverse movement. Chamber 21, orifice 23, valve stem 27, and opening 38 are axially aligned.

The end of body portion 20 opposite orifice 23 is open and internally threaded to receive a plug 39. Plug 39 is screwed into threaded chamber 21 to hold guide member 36 in a fixed position and is sealed between it and body portion 20 by means of a conventional gasket 41. Plug 39 is also internally threaded to receive a threaded conduit 42 transmitting liquid under pressure to chamber 21.

In operation, the size of the outlet orifice 23, the strength of the spring 32 and the mass of the spring 32 and valve member 27 are so co-related to one another and to a given liquid pressure within chamber 21 that valve member 27 is maintained in forced vibration as part of a resonant system. Liquid passes through orifice 23 and is transformed into a fine spray or fog which passes from inside cap 26 through openings, such as openings 34, to the surrounding area. Openings 34 may be angularly positioned in cap 26 to serve as a guide for ejecting the spray in the direction desired.

Although various sections of the nozzle of

Figure 3 have been connected by threading the parts and screwing them together, other methods, such as bolting or welding, may be used and without departing from the scope of this invention.

Preferably the included or apex angle formed by the conically-shaped portion of the valve heads of the nozzles shown in Figures 1 and 3 is between 60 and about 150 degrees; the actual angle best suited for any particular valve head will depend on such factors as the size of the orifice and the pressure of the liquid being atomized. Included angles between 90 and 120 degrees for the valve heads have shown best results.

In operation, the potential energy available from the pressure of the liquid is consumed by the friction of the liquid passing through the nozzle and by the energy necessary to cause vibration of the valve member. For maximum efficiency, therefore, it is desirable to reduce the energy losses to a minimum. The greater the proportion of the total energy available for use in vibrating the valve member, the higher the frequency of vibration that can be obtained which results in the maximum dispersion of the liquid as a spray or fog for a given pressure. In fact, if energy losses are too great the valve member will not vibrate. Accordingly, the dimensions and shapes of such elements as the orifice, the chamber and valve member are important and the following dimensions serve as a guide for the construction of a nozzle having minimum frictional losses. The downstream end of the chamber is preferably in the form of a 90 to 120 degree cone to minimize the turbulence of the liquid as it passes from the chamber to the discharge orifice. The longitudinal length of the orifice is preferably as short as structural limitations will permit, usually from about $\frac{1}{4}$ to about $\frac{1}{4}$ of an inch in length, although shorter or longer dimensions may be used. The diameter of the orifice should not be so small as to cause excessive energy losses by the passage of liquid therethrough. Generally, the diameter of the orifice will be between about $\frac{1}{16}$ and about $\frac{1}{2}$ inch, but larger or smaller diameter orifices may be used depending on such factors as the pressure of the liquids and the capacity of the nozzle. The diameter of the valve head is only slightly larger than the diameter of the mouth of the orifice in order to insure uniform particle size. If the valve head is too large in diameter as compared to the orifice diameter, the surface area of the conical section of the valve head projects too far over the edge of the orifice, as a result the liquid particles produced by the vibration action cling to the under surface of the valve head agglomerating the fine particles. Preferably, the diameter of the valve head is not more than $\frac{1}{2}$ of an inch larger than the diameter of the orifice. For example, a valve head not greater than $\frac{3}{8}$ of an inch in diameter should be used with an orifice $\frac{1}{8}$ of an inch in diameter.

The spray of the nozzle of Figure 1 of the drawing will form a cone having an included or apex angle slightly smaller than the included angle of the conical section of the valve head. The particle size of the spray is a function of the force, within a definite range, with which the spring urges the valve head towards the orifice. Thus, for a given pressure the particle size for the spray may be varied by changing the tension of the spring, which in the case of Figure 1 is accomplished by adjusting screw 17,

and in case of Figure 3 is accomplished by adjusting the position of housing or cap 26 on body portion 20.

Although the various structural materials used to make the nozzles form no part of this invention, it should be noted that the orifice and the valve member including the valve head may be made of special alloys, or plated or clad with such alloys, in order to minimize wear and erosion. A wear or erosion resistant sleeve made of a suitable wear resistant material, such as stainless steel, Monel metal, Stellite, or a jewel such as a sapphire, may be inserted and fitted in the orifice, if desired. It may also be desirable to make the valve member of softer material than the orifice, so that most of the wear will be on the valve member which can be replaced more readily than the body portion containing the orifice.

The atomizing nozzles shown in Figures 1 and 3 may be used on liquids at various pressures. Best results are obtained at pressures above about 100 pounds per square inch gage and up to pressures as high as the tension of the spring concerned with the orifice diameter will permit. Pressures as high as 6000 pounds per square inch gage have been used with the vibrating type nozzle of this invention with excellent results characterized by an efficiency as high as 80 percent and higher. For maximum capacities and finest sprays, pressures between 2000 and 6000 pounds per square inch gage are preferred for the nozzles shown.

A vibrating type nozzle similar in construction to that shown in Figure 1 which showed satisfactory performance had the following dimensions and operating characteristics: The nozzle had a 0.018 inch diameter orifice and a $\frac{1}{2}$ inch diameter valve head with a 120 degree cone. The chamber of the nozzle was about $\frac{3}{4}$ of an inch in diameter and about an inch long. At liquid pressures of about 3000 and 5000 pounds per square inch gage, this nozzle had an optimum capacity of 200 cc. per minute and an exceptionally high efficiency for spraying both water and oil. This nozzle used a steel bow spring having a by $\frac{1}{8}$ inch square cross-section and the length of that arm of the spring extending laterally above the orifice was about $3\frac{1}{2}$ inches.

Figure 4 of the drawings is a graph of comparative tests between the vibrating type nozzle of the present invention such as that described immediately above and the most efficient commercial nozzle tested. The selection of the most efficient commercial nozzle was based on tests made on many different nozzles commercially available on the market to determine which produced the most finely dispersed spray. Since the commercial nozzle selected operated most satisfactorily at 3000 pounds per square inch gage, comparative tests were made at that pressure between the commercial nozzle and the vibrating type nozzle. In these tests brine was sprayed into an enclosed chamber for one minute and the fog produced allowed to settle. Samples of the fog were taken at intervals during the settling period to determine what per cent of the brine originally sprayed remained in suspension after a definite time interval. Representative data obtained from sampling the spray at intervals was plotted as Figure 4 with the percent of the spray in suspension of the total liquid sprayed as the ordinate and the settling time in minutes as the abscissa. Curve A represents the results of the vibrating type nozzle at 5000 pounds per square

inch gage. Curve B represents the results of the vibrating type nozzle at 3000 pounds per square inch gage. Curve C represents the results of the most efficient commercial nozzle at 3000 pounds per square inch gage.

The curves of Figure 4 show that at 3000 pounds per square inch gage 64 per cent of the brine sprayed remained in suspension after spraying for one minute with the vibrating type nozzle of this invention and less than 11 per cent of the brine sprayed remained in suspension after spraying for one minute with the most efficient commercial nozzle. At 5000 pounds per square inch gage with the vibrating type nozzle 93 per cent of the brine sprayed remained in suspension after spraying for one minute. After ten minutes of settling at 3000 pounds per square inch gage, 27 per cent of the brine sprayed by the vibrating type nozzle was still in suspension as compared to 4 per cent of the brine sprayed by the most efficient commercial nozzle. Figure 4, gives a measurement of the amount of liquid atomized by the nozzles compared and indirectly a comparison of the fineness of the spray particles.

Various alterations and modifications of the nozzles illustrated, such as the size, shape, and the type of spring, may become apparent to those skilled in the art without departing from the scope of the invention. Various uses of the nozzle and its principle of operation are contemplated such as for the use in humidification, emulsification, milk spraying, spray drying, fuel injection, spray painting, powder metallurgy, surface cooling, fire extinguishing, distillation, etc. The vibrating principle of the nozzle in atomizing liquids has its obvious application as an integral part of equipment and appliances, such as, oil burners, internal combustion engines, fire extinguishers, etc. In any of these instances the nozzle portion of the apparatus is defined by the various associated parts necessary to produce a vibrating action of a valve member, the result of which vibrating action atomizes the liquid.

It is understood that the essence of the present invention is the employment of a vibrating member for atomizing of a liquid, and it is realized that there are many available ways other than those specifically disclosed herein for bringing about the desired results.

Having described my invention, I claim:

1. An atomizing nozzle comprising a body portion having a chamber within said body portion; a conduit supplying liquid under pressure to said chamber; an outlet orifice of smaller dimensions communicating with said chamber; a bow spring rigidly attached to said body portion, said bow spring extending over said outlet orifice, said bow spring having an aperture therethrough aligned with said outlet orifice; a valve member extending through said aperture and seating in said outlet orifice; and an adjusting screw urging said valve member towards said outlet orifice associated with a bracket rigidly attached to said bow spring, the arrangement being such that said valve member is maintained in forced rapid vibration by the pressure of said liquid acting on a resonant system comprising said spring and parts associated therewith.

2. An atomizing nozzle comprising in combination a body portion having a chamber within said body portion and a stationary outlet orifice having an edged seat and of substantially smaller cross-sectional dimension than said chamber, a movable valve member adapted to freely move

in its normal span of movement in a substantially longitudinal direction along the axis of said orifice and having a closed terminal portion terminating adjacent said orifice and seated on the edged seat of said outlet orifice, said terminal portion having a maximum diameter not greater than 1½ times the diameter of the orifice and an apex angle between about 60° and about 150° at its point of seating on said orifice, and a spring urging said movable valve member firmly into the seat of said outlet orifice.

3. An atomizing nozzle comprising in combination a body portion having a chamber within said body portion and a stationary outlet orifice having an edged seat and of substantially smaller cross-sectional dimension than said chamber, a movable valve member adapted to freely move in its normal span of movement in a substantially longitudinal direction along the axis of said orifice and having a closed terminal portion seated on the edged seat of said outlet orifice, said terminal portion having a maximum diameter not greater than 1½ times the diameter of the orifice and an apex angle between about 60° and about 150° at its point of seating on said orifice, and a U-shaped bow spring having substantially parallel legs urging said moveable valve member firmly into the seat of said outlet orifice.

4. An atomizing nozzle comprising in combination a body portion having a chamber within said body portion and a stationary outlet orifice having an edged seat, a moveable valve member adapted to freely move in a direction substantially perpendicular to said orifice and having a closed terminal portion of a diameter not greater than about $\frac{1}{2}$ of an inch greater than the diameter of said orifice seated on the edged seat of said outlet orifice and a helical spring urging said moveable valve member towards said outlet orifice.

5. An atomizing nozzle comprising in combination a body portion having a chamber within said body portion and a stationary outlet orifice having an edged seat, a moveable valve member adapted to freely move in a direction substantially perpendicular to said outlet orifice and having a closed terminal portion of a diameter not greater than about $\frac{1}{2}$ of an inch greater than the diameter of said orifice seated on the edged seat of said outlet orifice and a spring positioned externally of said chamber of said body portion urging said moveable valve member towards said outlet orifice.

6. An atomizing nozzle comprising in combination a body portion having a chamber within said body portion, a stationary cylindrical outlet orifice and a converging passageway in the form of a 90 to 120° cone leading from said chamber to said orifice, said orifice being between about $\frac{1}{16}$ and $\frac{1}{4}$ of an inch in length and between about $\frac{1}{64}$ and about $\frac{1}{2}$ inch in diameter and smaller in diameter than any preceding passageway of said body portion, a moveable valve member adapted to freely vibrate in a direction substantially perpendicular to said orifice and having a closed terminal portion in the form of a cone having an apex angle between about 60 and about 150° and a diameter of not more than $\frac{1}{2}$ of an inch larger than the diameter of said outlet orifice seated in said cylindrical outlet orifice and a spring urging said moveable valve member towards said orifice.

7. An atomizing nozzle comprising in combination a body portion having a chamber within said body portion, a stationary cylindrical outlet ori-

fice and a converging passageway in the form of a cone leading from said chamber to said orifice, said orifice being between about $\frac{1}{8}$ and $\frac{1}{4}$ of an inch in length and between about $\frac{1}{64}$ and about $\frac{1}{2}$ inch in diameter and smaller in diameter than any preceding passageway of said body portion, a moveable valve member adapted to freely move in a direction substantially perpendicular to said orifice and having a closed terminal portion in the form of a cone having an apex angle between about 60 and about 150° and a diameter of not more than $\frac{1}{2}$ of an inch larger than the diameter of said outlet orifice seated in said cylindrical outlet orifice and a spring urging said moveable valve member towards said orifice.

8. In an atomizing nozzle containing a closed moveable valve member seated on the edge of an orifice of said nozzle by the pressure of a spring, the method for improving the atomization of said nozzle which comprises supplying to said nozzle a liquid at a substantially constant pressure between about 100 and about 6000 pounds per square inch gage, vibrating said moveable valve member in a direction substantially perpendicular to the mouth of said orifice at a frequency of at least 60 cycles per second by using only the force supplied by the liquid under substantially constant pressure, and passing liquid through said orifice whereby the liquid is atomized by the vibration of the moveable valve member.

9. In an atomizing nozzle containing a closed moveable valve member seated on the edge of a cylindrical outlet orifice of said nozzle by the pressure of a spring, said valve member having a valve head not greater than $1\frac{1}{2}$ times the di-

ameter of the cylindrical outlet orifice, the method for atomizing a liquid by said nozzle which comprises supplying to said nozzle a liquid at a substantially constant pressure between about 2000 and about 6000 pounds per square inch gage, vibrating said moveable valve member in a direction substantially perpendicular to the mouth of said orifice at a frequency of at least 60 cycles per second by using only the force supplied by the liquid under substantially constant pressure, and passing liquid through said orifice whereby the liquid is atomized by the vibration of the moveable valve member.
